(57) **CLAIM**

The ornamental design for an angle adaptor for bicycle head tube, as shown and described.

DESCRIPTION

FIG. 1 is a top isometric view of an illustrative angle adaptor for bicycle head tube according to the present invention; FIG. 2 is an exploded top isometric view of the angle adaptor for bicycle head tube of FIG. 1;

FIG. 3 is a bottom isometric view of the angle adaptor for bicycle head tube of FIG. 1;

FIG. 4 is a front elevation view of the angle adaptor for bicycle head tube of FIG. 1;

FIG. 5 is a top plan view of the angle adaptor for bicycle head tube of FIG. 1;

FIG. 6 is a left side elevation view of the angle adaptor for bicycle head tube of FIG. 1;

FIG. 7 is a view of the angle adaptor for bicycle head tube of FIG. 1, taken along the line 7-7 in FIG. 6, and is at an angle of 1.44 degrees relative to the view in FIG. 5;

FIG. 8 is a bottom plan view of the angle adaptor for bicycle head tube of FIG. 1;

FIG. 9 is a rear elevation view of the angle adaptor for bicycle head tube of FIG. 1; and,

FIG. 10 is a right side elevation view of the angle adaptor for bicycle head tube of FIG. 1.

The design is limited to the angle adaptor for bicycle head tube and does not include the bicycle head tube with which it may be used. The portions shown in dashed lines form no part of the claimed design.
